DYNAMIC MULTIPLIER CIRCUIT

John Hays Hammond, Jr., Gloucester, Mass., assignor to Hammond Holding Corporation, Gloucester, Mass., a corporation of Delaware

Application November 1, 1930, Serial No. 492,661
Renewed September 28, 1933

13 Claims. (Cl. 179—100.1)

This invention relates to amplifying systems and more particularly to an improved system for controlling the amount of amplification in accordance with the strength of the applied energy.

5 The invention relates particularly to a system of amplification in which a greater ratio of amplification or gain is produced for impressed signals of high intensity than for impressed signals of low intensity.

10 The invention provides means for varying the impedance external to a space discharge amplifier by changing the impedance of a control device associated therewith, thus causing the amplification of the system to vary in accordance 15 with the input signal strength.

The invention also consists in certain new and original features of construction and combinations of parts hereinafter set forth and claimed.

Although the novel features which are believed 20 to be characteristic of this invention will be particularly pointed out in the claims appended here- 20 to, the invention itself, as to its objects and advantages, the mode of its operation and the manner of its organization may be better understood 25 by referring to the following description taken 25 in connection with the accompanying drawing forming a part thereof, in which

The single figure illustrates diagrammatically 30 the system as applied to the reproduction of the sound record of a talking moving picture projector or of a phonograph.

In the following description and in the claims, 35 parts will be identified by specific names for convenience, but they are intended to be as generic in their application to similar parts as the art will permit.

Referring more particularly to the accompany- 40 ing drawing, a source of illumination 10 is pro- 40 vided, the light from which is focused, by means 45 of a lens 11, through an aperture 12 in an aper- 45 ture plate 13, and upon the sound record of a 50 moving film 14. The light which passes through 50 this film is focused by means of a lens 15 upon a 55 photoelectric cell 16. This cell is connected 55 through a transformer 17 to one side of a double- 60 pole double-throw switch 18, the other side of 60 which is connected to a phonograph pick up 19.

The blades of the switch 18 are connected 65 through a transformer 21 to the input circuits of 65 two space discharge tubes 22 and 23 which are 70 connected in parallel to a common filament bat- 70 tery 24 and a common biasing battery 25. The 75 output circuit of the space discharge tube 22 (which may be called the amplifier tube) in- 75 cludes a plate battery 26, and the primary of a

transformer 27, the secondary of which is connected to the input circuit of a push-pull amplifier 28. The output circuit of this amplifier 28 is connected through a transformer 29 to the moving coil of a loud speaker 31. The field winding 32 of this loud speaker is supplied with current from a battery 33.

The output circuit of the space discharge tube 23 (which may be called the first control tube) includes a plate battery 35 and a resistance 36 10 which is shunted by a condenser 37. One side of the resistance 36 is connected to the input circuit of a third space discharge tube 38 (which may be called the second control tube), the output circuit of which is connected in parallel with 15 the output circuit of the space discharge tube 22. The filament of the space discharge tube 38 is also heated by the battery 24.

In the operation of the form of the invention 20 shown in the accompanying figure, when it is 20 desired to use the photoelectric pick up, the switch 18 is thrown to the upper position, and when it is desired to use the phonograph pick up, this switch is thrown to the lower position. In either case, the energy received passes through 25 the transformer 21 to the input circuits of the space discharge tubes 22 and 23. The amplified output from the amplifier tube 22 passes through the primary of the transformer 27 and the space 30 discharge tube 38. The energy from the second- 30 ary of the transformer 27 passes to the push-pull 35 amplifier 28 where it is further amplified. The output from this device 28 then passes through the transformer 29 to the moving coil of the loud 35 speaker 31 where it is reproduced as speech or 35 music in the usual manner.

Part of the input energy passes to the first 40 control tube 23 which acts as a detector causing 40 current to flow in the direction of the arrow 45 through the resistance 36, thus building up a 45 potential difference across it which is proportional to this current and, therefore, proportional 50 to the input signal strength.

With low intensity input signal the negative 45 potential applied to the grid of the second con- 45 trol tube 38 due to the current in the resistance 36 is small, thus causing the impedance of the 50 second control tube 38 to be small which in turn 50 allows a large current to flow through this device. In this way a considerable proportion of the out- 55 put of the amplifier tube 22 passes through the 55 second control tube 38, thus reducing the amount 55 of energy passing through the transformer 27 which cuts down the output of the loud speaker 55

31. In this way the amplification ratio of the system is decreased.

With increase of signal strength, more current will flow through the resistance 36, thus increasing the negative potential applied to the grid of the second control tube 38 which causes an increase of its impedance, thus reducing the current flowing through it. This causes less of the output of the amplifier tube 22 to be shunted 10 through the second control tube 38, and therefore, a greater proportion will pass through the transformer 27 to cause an increase of volume in the loud speaker 31. In this way the amplification ratio of the system is increased.

15. It is thus seen that, with low input signal strength, the amplification ratio of the system will be low due to a decrease in the impedance external to the amplifier, thus causing a large proportion of the output energy of the amplifier 20 to be by-passed through the device 38. With high input signal strength the amplification ratio of the system will be high due to an increase of the external impedance which allows only a small proportion of the output energy to be by-passed.

25. Although only a few of the various forms in which this invention may be embodied have been shown herein, it is to be understood that the invention is not limited to any specific construction, but might be embodied in various forms 30 without departing from the spirit of the invention or the scope of the appended claims.

What is claimed is:

1. In a system for reproducing sound from a record, a space discharge device, a second space 25 discharge device in parallel therewith, a resistance in the plate circuit of said second device, a third space discharge device, said resistance being also in the input circuit of said third space discharge device, the output circuit of said third device being in parallel with the output circuit of 40 said first device.

2. In a system for reproducing sound from a record, a space discharge device, a second space 45 discharge device having an output circuit, said output circuit forming a shunt path for the output of said first device, a third space discharge device having an input circuit said input circuit being in parallel with the input circuit of said first device, a resistance in the output circuit of 50 said third device said resistance also being in the input circuit of said second device.

3. In a system for reproducing sound from a record, an electron discharge device having an output circuit, a second electron discharge device 55 also having an output circuit, both of said output circuits being connected in parallel, a third electron discharge device having an input circuit which is in parallel with the input circuit of said first device, a resistance in the output circuit of said third device which is also in the input circuit of said second device and means for varying the current in said resistance in accordance with the input signal strength, thus varying the impedance 60 of the second device which varies the amplification ratio of the first device.

4. In a system for reproducing sound from a record, an electron discharge device having a control element, a source of signal, means for impressing said signal on said control element, a second electron discharge device having a control element, means for impressing said signal on the control element of said second device, a resistance in the path of the space current of said 70 second electron discharge device, a third electron 75

discharge device having a control element, said resistance being so arranged that the voltage drop therein caused by the space current of the second electron discharge device controls the potential applied to the control element of the third electron discharge device and means for varying the external impedance of said first device by the change of impedance of said third device due to the variation of potential applied to the control element thereof.

5. In a system for reproducing sound from a record, an electron discharge device having a control element, a source of signal, means for impressing said signal on said control element, a second electron discharge device having a control element, means for impressing said signal on said second device, a resistance in the path of the space current of said second electron discharge device, a third electron discharge device having a control element said resistance being so arranged that the voltage drop therein caused by said space current controls the potential applied to the control element of said third electron discharge device, thus varying the impedance of said third device which causes a variation of the amount of energy shunted from the output circuit of said first device thus controlling the amplification ratio of said first device so that it is greater for strong signals than for weak ones.

6. In a system for reproducing sound from a record, an amplifier tube, first and second control tubes, each tube having an anode, a cathode and a control electrode, means for impressing a signal on the cathode-control electrode circuits of said amplifier tube and said first control tube, a first source of B-voltage and a resistance in the anode-cathode circuit of said first control tube, a capacitance across said resistance, said resistance being in the control electrode-cathode circuit of said second control tube, a second source of B-voltage and an output device in the anode-cathode circuit of both said second control tube and amplifier tube.

7. In a system for reproducing sound, a sound record, a pick-up device therefor, a space discharge amplifier fed by said pick-up device and means for varying the average external impedance of said amplifier in accordance with the average strength of the signals fed to said amplifier, thus varying the amplification ratio of said 50 amplifier for strong and weak signals.

8. In a system for reproducing sound, a sound record having moderate contrast between loud and soft notes, a pick-up device therefor, a space discharge amplifier having an input circuit fed by said pick-up device and also having an output circuit, a variable impedance device shunted across said output circuit and means controlled by the average strength of the signal impressed on said input circuit for determining the average 60 impedance of said impedance device, thus varying the amplification ratio of said amplifier so that it is greater for strong signals than for weak signals.

9. In a system for reproducing sound, a sound record having a moderate volume ratio between loud and soft notes, a pick-up device therefor, a space discharge amplifier having an input circuit fed by said pick-up device and also having an output circuit, a second space discharge amplifier having its anode circuit in said output circuit and means controlled by the average strength of the signals impressed on said input circuit for determining the average impedance of said second 75

amplifier, thus varying the amplification ratio of said first amplifier so that it is greater for strong signals than for weak signals.

10. The method of operating a space discharge amplifier in the reproduction of sound from a sound record which comprises varying the average external impedance of said amplifier in accordance with the average strength of the signals fed to said amplifier, thus varying the gain ratio 10 of said amplifier for strong and weak signals.

11. In a system for reproducing sound, a sound record having moderate contrast between loud and soft notes, a pick-up device therefor, a space discharge amplifier having an input circuit fed by said pick-up device and also having an output circuit, a variable impedance device adapted to vary the impedance of said output circuit, and means controlled by the average 15 strength of the signal impressed on said input

circuit for determining the average impedance of said impedance device.

12. The method of operating a space discharge amplifier in the reproduction of sound from a sound record which comprises amplifying the sound energy received from said record in said amplifier while varying the external impedance of said amplifier in accordance with the strength of the input signal so as to expand the volume ratio of the output of the amplifier with respect 10 to the input thereof.

13. The method of reproducing sound from a sound record which comprises picking up the energy variations of said record, applying said variations to a space discharge amplifier, varying 15 the external impedance of said amplifier in accordance with the strength of said energy variations, and applying the output of said amplifier to a translating device.
